ALKYLATION PROCESS

Fred Hederhorst, Baytown, Tex., assignor to
Standard Oil Development Company, a corpora-
tion of Delaware

Application September 25, 1940, Serial No. 358,204

8 Claims. (Cl. 196—10)

The present invention relates to a method for producing high octane number isoparaffinic hydrocarbons, particularly those boiling within the motor fuel boiling range, by the catalytic alkylation of isoparaffins with olefins. The process is an improvement in the production of such motor fuels by alkylation in connection with the use of concentrated sulfuric acid as the catalyst.

It has been previously known that saturated high octane number isoparaffins such as, for example, the iso-octanes, could be produced by reacting low molecular weight isoparaffins such as isobutane or isopentane with olefins such as propene, butenes, pentenes, their polymers and copolymers, and the like, in the presence of strong sulfuric acid, that is, having concentrations between about 90% and about 100.6%, and at temperatures between about 0° F. and about 100° F. It has heretofore been considered essential in conducting such reactions to maintain the titratable acidity of the sulfuric acid between about 90% and about 100.6% by weight of sulfuric acid in order to obtain optimum results. By following this procedure it is possible to obtain high yields of iso-octanes when reacting isobutane with butenes. Ordinarily, the catalyst concentration is maintained between about 90 and 95 weight per cent of sulfuric acid while carrying out such reactions by the addition of sufficient amounts of strong makeup acid or by the addition of sulfur-containing dehydrating agents such as, for example, sulfur trioxide, fuming sulfuric acid and similar compounds. The necessity for maintaining the above-specified catalyst concentrations has been thought heretofore to be universally applicable to the aliphatic alkylation process regardless of the reactants employed. No different acid concentrations were considered to be useful for alkylating isopentane in contrast to the alkylation of isobutane. Likewise, in the case of the olefinic reactants the required catalyst concentration was considered to be the same whether the olefin employed was propene, the butenes, the pentenes or the normally liquid monoolefinic hydrocarbons.

It is an object of the present invention to secure hitherto unexpected high yields of substantially completely saturated branched chain, normally liquid hydrocarbons boiling within the motor fuel range and having high octane numbers by employing acid of varying concentrations within said ranges and correlating the various concentrations of acid with respect to the particular olefins fed to the reaction zone so that the quality and yields of product are not im-

paired yet the acid has a longer useful life with respect to its alkylating activity.

It is a further object of the invention to produce high yields of substantially completely saturated, branched chain, normally liquid hydrocarbons first from normally gaseous isoparaffins and olefins followed by the production of substantially the same quality material in high yields by the use of the spent catalyst from said reaction as an alkylation catalyst for the reaction of normally gaseous or liquid isoparaffins with normally liquid monoolefins. It is a further object of the invention to substantially increase the effective alkylation activity life of concentrated sulfuric acid while obtaining high yields of desired saturated hydrocarbon products.

To accomplish the aforementioned objects as well as others which will be apparent upon a full understanding of the herein disclosed invention, it has been found advantageous to employ a sulfuric acid catalyst that is no longer sufficiently strong to produce optimum yields and quality of alkylate from isobutane reacted with butenes or from isobutane reacted with propene for alkylating isoparaffins such as, for example, isobutane or isopentane and higher isoparaffins, with pentenes and higher monoolefinic hydrocarbons even to the point where the acid strength or titratable acidity falls to as low as between about 82 and about 89%. In the alkylation of isoparaffins and olefins, after a period of time the sulfuric acid catalyst becomes contaminated with organic material which accordingly decreases its titratable acidity. Below about 90% titratable acidity the acid catalyst is no longer economically effective for alkylating isobutane with normally gaseous monoolefins. This catalyst has unexpectedly, however, been found to be effective in catalyzing the reaction of isoparaffins including isobutane with normally liquid monoolefins such as, for example, the pentenes and higher homologues.

In general, the reaction may be described as follows, although the specific reactants, temperatures and the like are illustrative only and not considered limitative of the invention: Isobutane admixed with butenes may be introduced into an alkylation reactor with a sulfuric acid catalyst having a titratable acidity between about 90% and about 95%. Vigorous agitation of the reaction mixture is maintained and the heat of reaction is removed by evaporation of a portion of the hydrocarbons, thus maintaining the temperature by means of pressure regulation between about 20° F. and about 80° F., preferably 35° F.

Any vapors which are removed from the reactor may be caustic washed, compressed, cooled and returned to the reactor. The product is withdrawn from the reactor in the form of an emulsion of light hydrocarbons, product and acid catalyst. A portion of the emulsion may be returned to the reactor to maintain a high ratio of isoparaffins to olefins in the reaction mixture. The remainder of the withdrawn emulsion is settled in a settler. The acid is separated and a portion or all of the same may be returned to the alkylation reactor together with an amount of strong fresh makeup acid if desired sufficient to maintain the titratable acidity of the catalyst at the desired level. The normally liquid product removed from the acid settler is caustic washed and fractionated. The lighter fractions which may contain considerable amounts of unreacted reactants may then be recycled to the reactor and the desired alkylation product recovered as a high octane number motor fuel. In a second reactor a feed stock containing isobutane, isopentane, or some suitable isoparaffin or mixture of isoparaffins, together with one or more normally liquid monoolefins such as, for example, the pentenes either as pure hydrocarbons or as commercial mixtures (a suitable feed stock being a C₅ cut containing isopentane and pentenes or isobutane with pentenes) is introduced with an acid catalyst of between about 80% and about 89% by weight of sulfuric acid, preferably, however, within the range between about 85% and about 87% sulfuric acid. As in the first reactor, the heat of reaction is removed by controlling the pressure so that by the evaporation of a portion of the lighter hydrocarbon feed the desired temperature is maintained in the reactor. Any other suitable temperature control means may be employed. As before stated in connection with the first alkylation zone, the lighter hydrocarbons may be caustic washed, compressed, cooled and returned to the reactor. Vigorous agitation is maintained and the emulsion is withdrawn from the reactor, settled, and the recycling as described above for the first alkylation stage is carried out substantially as therein described. The settled acid is returned to the reactor and the strength is maintained at the desired level by the addition of further quantities of acid previously withdrawn from the isobutane-butenes alkylation zone heretofore described. If desired, all of the acid employed in the second alkylation stage may be obtained from the first alkylation stage once that acid has substantially lost its optimum catalytic effect for the first stage reactants. The normally liquid product withdrawn from the second acid settler is then treated as described in connection with the first alkylation stage. Acid which has become so spent in the second alkylation stage as to be practically of no utility in that stage may either be employed in a third alkylation stage employing still more reactive olefins or it may be withdrawn and discarded as unfit for utilization in further alkylation reactions but may be used in other petroleum treating operations or it may be reconcentrated for use in the alkylation described in connection with the first alkylation stage, and so on.

In describing the process of the present invention, the sulfuric acid concentration has been described with reference to the weight per cent of sulfuric acid in the composition. It is important, however, to understand that the weight per cent of sulfuric acid in the composition is not entirely an accurate method of measuring

the utility of the sulfuric acid composition for catalytic alkylation activity. Titratable acidities of the sulfuric acid catalysts are really measures of the percentage of free sulfuric acid in the acid composition. The lowered titratable acidity of the alkylation catalyst after continued use in an isoparaffinolefin condensation process is due to the build-up or increase in amount of organic material contained in that catalyst composition. The lowered titratable acidity is not, however, due to any substantial increase in the amount of water present in that composition. If the titratable acidity of sulfuric acid is lowered to approximately 83-89% by dilution with water, it will not effectively catalyze either the butenes or pentenes type of alkylation reaction. In general, the catalysts employed in the reaction even though spent with respect to the first stage of alkylation seldom contain more than about 5% or 6% by weight of water and usually less, the remainder of the titratable acidity loss being accounted for by the build-up of organic impurities in the composition.

EXAMPLE 1

In order to illustrate the relatively poor catalytic effects of sulfuric acid in which the titratable acidity has been reduced by dilution with water rather than by dilution with organic matter, the following data were obtained on the alkylation of isobutane with pentenes in which the sulfuric acid weight per cent concentration was 84.2% and 89.5% titratable acidity containing no organic matter. These data are compared with data obtained in an alkylation experiment where sulfuric acid of 97.3% by weight was the catalyst and which also contained no organic matter. The temperature for carrying out the reaction was about 68° F. with a total contact time of about 120 minutes, the olefinic portion of the feed stock being added to the intimately mixed acid-isoparaffin composition.

Isobutane-pentene treats employing sulfuric acid diluted with water as catalyst

	Run No.		
	A	B	C
Initial acid strength, percent	84.2	89.5	97.3
Vol. acid/vol. olefin	12.0	12.1	8.9
Composition of total feed stock, vol. percent:			
Butenes	0.3	0.3	0.1
Isobutane	74.5	74.5	74.4
n-Butane	10.7	10.7	10.3
Pentenes	4.1	4.1	5.6
n-Pentane	5.1	5.1	6.6
Isopentane	4.5	4.5	2.6
Ratio: Isoparaffin/olefin	18.0	18.0	13.3
Vol. percent yield C ₄ -free product, based on olefin charge	106	148	169
Distribution of product, liq. vol. percent:			
Initial boiling point-110° F	56.6	51.6	45.6
110-235° F	11.8	34.8	46.1
235° F.-final boiling point	31.6	43.6	8.3
Inspections on product:			
A. S. T. M. octane number	80.7	82.5	82.4
Bromine number	29	0.6	0.7
Initial boiling point, °F	86	92	106
Final boiling point, °F	92% off at 406°	440	358

These data indicate a considerable drop in yield, a poor product distribution and a low overall octane number of the product produced when using sulfuric acid of reduced strength caused by the addition of water. In Run A, wherein the catalyst had 84.2% concentration comprising water and acid, a large percentage of the final product was olefin polymer rather than alkylation

tion product as evidenced by a bromine number of 29.

In another run, a feed stock comprising isobutane and pentenes was alkylated at about 55° F. in a jet type continuous unit with no acid replacement. The emulsion recycle ratio, that is, the volumes of acid-hydrocarbon per volume of fresh acid, was about 11.2 with no product recycled. The ratio of fresh feed in volumes per unit volume of the reactor per hour was about 0.68, the fresh feed containing about 11.4% unsaturates and having an isobutane to pentenes ratio by volume of about 4:1. This particular apparatus was a continuous unit which operated for a total of 45 hours. At the end of 27 hours of operation the yield of C₅-free alkylate by volume based upon the total olefins added up to that time was about 165% and the titratable acidity of the acid in the reaction mixture was about 87.4. However, the acid composition was substantially anhydrous in character. After a total of 43 hours of continuous operation, the titratable acidity of that same acid was about 82.7% and the yield of C₅-free alkylate by volume was about 175% based on the olefins added. Of this product approximately 77.2% constituted a C₅-free fraction boiling between 105° F. and 310° F. and it had an octane number of about 87.7 and a bromine number of about 0.86. These results show that although the titratable acidity was in the same range as in the case of Run A, but wherein the reduction in titratable acidity was caused by a build-up of organic material rather than by dilution with water, the alkylating activity of that catalyst was better than one having a titratable acidity of 89.5 (Run B) but wherein the remainder of the composition was substantially water as shown in the preceding table. Note also that the bromine numbers of the products as between a titratable acidity of 84.2 in Run A and 82.7 in the present run were 29 and 0.86 respectively. The acid catalyst in the present run decreased in titratable acidity from an initial concentration of 96.5 to a titratable acidity of 88.2 in the first 15 hours of operation, and this was almost solely due to a build-up of organic material from the reaction of isobutane with pentenes. The percentage decrease in titratable acidity due to the formation of water in the catalyst composition is almost negligible.

EXAMPLE 2

The following data show the permissible limits of titratable acidity for the alkylation reactions involving the use of butenes and for the alkylation reactions involving the use of pentenes. The alkylation of isobutane with butenes in the presence of 90 to 95% sulfuric acid will produce optimum yields and quality of product. When this acid is no longer an efficient catalyst for this reaction, it is then possible to utilize the acid without purification directly as an effective catalyst for the alkylation of isoparaffins with pentenes. This makes the present invention advantageous in that a more economical operation is obtained in an alkylation unit by reason of the fact that the necessity for a dual acid catalyst system is eliminated and the alkylation of butenes occurs separately yet simultaneously with the alkylation of pentenes.

An isobutane-butenes alkylation reaction was catalyzed in a jet type alkylation unit with sulfuric acid having an initial acidity of approximately 92.0%; the acid in the system had been

used for alkylating butenes and its strength had been maintained at approximately 92.0% by discarding a portion of the acid in the system and replacing with fresh 96.5% acid. The reactor was maintained at a temperature of about 57° F. and the fresh-feed rate amounted to about 1.07 volumes of fresh feed per unit volume of the reactor per hour with an average recycle ratio, that is, recycle of volumes of acid-oil emulsion to volumes of fresh feed, of about 9.9:1. The fresh feed contained about 9.1% of olefins, chiefly butenes, with an isoparaffin to olefin ratio of about 5:1. At the end of 24 hours of continuous operation after discontinuing fresh-acid replacement the titratable acidity of the acid dropped to about 89.3, the yield of C₄-free alkylate based on the olefins was about 159% by volume, and the octane number of the product was about 92.5. Continued usage of the acid catalyst composition eventually lowered the titratable acidity to 87.0% with an alkylate yield of 142% which had an octane number of 91.7. When the catalyst composition after long usage had reached a titratable acidity of about 82%, the yield amounted to about 109%, of which 30% of the product boiled above the C₈ fraction. It is clearly evident from this that decreased yield, unfavorable product distribution, and lowered octane number of the alkylate occur when the titratable acidity of the catalyst falls much below 88 or 89% in cases where butenes are being alkylated. As in all alkylation reactions of the type herein specified, the decrease in the titratable acidity is largely due to the increase in the organic material present in the catalyst composition, the percentage of water in any given catalyst composition remaining substantially constant, that is, it does not vary much more than 1/2% to 1% from the original water content of the present catalyst. As previously pointed out, acid strengths of as low as 83% titratable acidity are capable of successfully catalyzing the isoparaffin-pentenes alkylation, yet in the case of butenes alkylation an acid strength of 89.3% by weight of sulfuric acid after 24 hours of operation without replacement of spent catalyst resulted in just about the lowest permissible titratable acidity limit for this reaction.

In another run carried out while employing isobutane and pentenes in a similar unit maintained under substantially the same reaction conditions and carried out in substantially the same manner, wherein the initial acid concentration was about 96.5% and wherein the fresh feed contained about 7.7% by volume of olefins, largely pentenes with a 7.5:1 isoparaffin to olefin ratio, the fresh feed was charged at a rate of about 4 litres per hour and the product continuously withdrawn over a total period of about 116 hours of operation of the original catalyst composition. For the first 68 hours of operation the titratable acidity very gradually dropped from the original percentage to a total of about 84.9%, at which time the total alkylate yield dropped only from about 183% to 180% by volume. The octane number of the 105-265° F. fraction dropped in this same period from about 91.1 to about 90.7. However, as the titratable acidity dropped below 84.9% (to around 82.1%) the yield of total alkylate immediately dropped to around 164% by volume and the octane number of the 105-265° F. fraction dropped to around 89.1. At the end of 116 hours the titratable acidity was around 59.7, the alkylate yield had dropped to 51% by volume based on the olefins, and the octane number of the 105-265° F. fraction was below 87. With the excep-

tion of about 3/4% of water, the remaining material which contaminated the product was composed of organic impurities contained in the acid layer by reason of the alkylation reaction. It will thus be seen that where the titratable acidity drops below 82-84% the quality of the product and the yield thereof drop off sharply.

The reactions as above described may be carried out in any suitable type of apparatus which has heretofore customarily been employed for the polymerization of olefins, the alkylation of isoparaffins with olefins and treating operations involving the use of sulfuric acid.

The accompanying drawing is a more or less diagrammatic representation of one simple type of apparatus which may be employed for carrying out the present invention. The drawing will be described in order to present a better understanding of the invention. A feed stock containing one or more monoolefins having four or less carbon atoms per molecule together with suitable isoparaffin components is introduced into the reactor 5 by means of lines 2 and 4 controlled by valve 3. Simultaneously with the introduction of the feed stock, the sulfuric acid catalyst of the desired concentration, for example, from 90% to about 100.6%, is introduced into the reactor 5 by means of lines 28, 18 and 4 controlled by valves 21 and 19. The mixture of feed stock and catalyst is adequately mixed upon being introduced into reactor 5 by any suitable means, for example, jets, turbo mixers, centrifugal arrangements, porous thimbles, or any other suitable type of mixing device. The emulsion which is formed is allowed to accumulate in reactor 5 until it overflows through lines 6 and 7 controlled by valve 8. The emulsion may then be recycled by means of circulating pump 9 back to reactor 5 through lines 10 and 4 controlled by valve 11, valve 13 in line 12 being closed. After the emulsion has been agitated and recycled a sufficient number of times, all or a portion of it may be withdrawn from the circulating system by opening valve 13. Any of the unreacted gases or the lighter products which may be contained in reactor 5 may be drawn off through line 24, controlled by valve 25 to maintain the desired temperature, and sent to a suitable recovery plant. The reacted emulsion upon entering settler 14 is separated into an upper hydrocarbon layer of alkylate and a lower acid layer which may be either returned to the reactor 5 for further use, providing its titratable acidity has not decreased below its point of usefulness, by means of lines 15, 16, 18 and 4 controlled by valves 17 and 19. In the event that the acid has lost its substantial utility in the reaction, it may be passed on to a second alkylation unit by means of line 46 controlled by valve 47. The alkylate from settler 14 is withdrawn through line 22 controlled by valve 23, caustic washed, and fractionated to give the desired fractions. Any of the undesired product or unreacted reactants contained in feed products which are separated by fractional distillation treatment may be either recycled to reactor 5 in the desired proportions or they may be employed in another alkylation unit or in some conventional manner.

Into the second alkylation unit there is introduced by means of lines 26 and 28 controlled by valve 27, valve 45 remaining closed, a feed stock containing isoparaffins and at least one monoolefin containing at least 5 carbon atoms per molecule. The actual arrangement of the apparatus is substantially identical with that previ-

ously described in connection with the olefin having 4 carbon atoms or lower per molecule. The reactor 29, which contains mixing devices previously described with reference to reactor 5, is a time tank having an overflow pipe 30 controlled by valve 32 and a recycle emulsion line 31 equipped with circulating pump 33 for the return of the emulsion to the reactor 29 by means of lines 34 and 28 controlled by valve 35. The acid catalyst employed in this reactor comes from the previous alkylation unit by means of lines 46, 44 and 28 controlled by valves 47 and 45. As in the previous reactor the emulsion is recycled through line 31 to the reactor 29 until such time as a substantial equilibrium has been reached, at which time a portion or all of the unreacted emulsion is withdrawn through line 38 controlled by valve 39 into settler 40. Any gaseous products of the reaction or unreacted gaseous constituents of the feed stock are withdrawn from the reactor 29 through line 36 controlled by valve 37 and, as has been described in connection with the effluents through line 24 controlled by valve 25, an economical use of the effluents may be made. The reacted mixture is allowed to settle in settler 40. The acid catalyst, if of sufficient activity to permit its reuse in the reactor 29, is returned to said reactor by means of lines 41, 42, 44 and 28 controlled by valves 43 and 45, valve 51 remaining closed. On the other hand, if the catalyst composition has become sufficiently spent as to lose its substantial utility in the present reaction, it may be discarded or it may be in turn introduced into a third alkylation system similar to the two herein described through line 50 controlled by valve 51, in which still more reactive olefins are introduced in the presence of suitable isoparaffins and the acid used in that reaction until its usefulness is no longer adequate, in which case it may either be discarded, sent to an acid recovery plant or employed in various sulfuric acid refinery treating operations. The alkylate from settler 40 is withdrawn through line 48 controlled by valve 49, caustic washed and fractionated into the desired fractions. The motor fuel fractions may be used as such, blended with desired fractions processed from line 22, blended with extraneous naphtha, etc. Heavier fractions may be recycled to either reactors 5 or 29 or to both reactors.

Although it is preferred to employ isobutane and mixtures containing isobutane as the paraffinic reactants, it is distinctly understood that isopentane and similar higher homologues containing at least one tertiary carbon atom per molecule may be employed. These higher homologues are especially desirable as reactants where it is desired to produce safety fuels, aviation naphthas, blending agents for motor fuels, and the like. The olefinic reactants may comprise ethylene, propylene, normal butylenes, isobutylene, trimethyl ethylene, the isomeric pentenes and similar higher monoolefinic hydrocarbons of either a straight chain or branched chain structure as well as their corresponding normally liquid polymers, interpolymers, copolymers, such as diisobutylene, triisobutylene, the codimers of normal butylenes and isobutylene, and the like. Mixtures of two or more of the olefins and of the paraffins as well are also particularly adapted for use in the reaction with certain reservations hereinafter to be described. Thus it is possible to employ C₂, C₃, C₄ and/or C₅ cuts from thermal and/or catalytic cracking units, field butanes which have been subjected to prior isomerization

and partial dehydrogenation treatments, refinery stabilizer bottoms, spent gases, and liquid products from alkylation units, catalytic polymerization and copolymerization units, and the like. With regard to the manner of feeding the olefins to the various reactions, it may be stated that the process can be operated so that ethylene and propylene are introduced into the first reactor, that is, the reactor containing the strongest sulfuric acid, the butylenes into the second reactor, and the pentenes and higher olefins into the third reactor, or the C₂, C₃ and C₄ olefins may all be introduced into a first reactor while the C₅ and heavier olefins are introduced into a second reactor. For economic reasons it may be preferred to employ the isoparaffin corresponding to the olefin introduced into any particular alkylation stage, that is, isobutane is ordinarily contemplated as being introduced with the butenes, isopentane with the pentenes, and so on. The reason for this is that in the ordinary refinery, as it is at present constructed, it is found to be quite expensive to separate C₅ paraffins from C₅ olefins, C₄ paraffins from C₄ olefins, etc., hence for economical reasons the olefin-paraffin cuts containing the same number of carbon atoms per molecule are usually desirable as such for feeding to the alkylation stages. However, it is within the scope of this invention to alkylate C₅ isoparaffins with C₄ olefins and C₄ isoparaffins with C₅ olefins.

The temperature maintained in the alkylation reactors in the various stages may either be uniform with regard to the various stages or there may be a temperature gradient maintained between the various stages. Thus, for example, the reactors may be maintained at between about 30° F. and about 85 or 90° F., or the first reactor involving the alkylation of propylene may be maintained at between about 55° F. and about 75° F., with the butene alkylation stage being maintained between about 35° F. and about 45° F., and the pentenes and heavier alkylation stages being maintained between about 50 F. and about 60° F. Stronger acids, of course, are in general employed in connection with the lower molecular weight olefins, whereas the reactivity of the higher olefins appears to be catalyzed sufficiently by the use of acid of reduced titratable acidity. The temperature may be controlled by means of pressure where the reaction mixture contains readily volatilizable hydrocarbons, or the reactors may be jacketed and cooled with brine or in any other suitable conventional manner.

The length of contact of the catalyst with the hydrocarbon reactants of course depends to a considerable extent upon the temperature of the reaction and the titratable acidity of the acid as well as the intensiveness of the agitation of the reactants with the catalyst mass. In general, the contact time is maintained between about 0.10 and about 1.50 hours. The reactions may be carried out in either the liquid or vapor phase, although for commercial operations liquid phases appear to be the more feasible.

Especially in the alkylation of isobutane with C₄ olefins the use of excess isobutane is desirable not only because of the fact that excess isoparaffins in general are beneficial to the production of high yields of the desired alkylates but also by employing such excesses of isobutane the pressures can be controlled so that with the vaporization of the excess isobutane the reaction mixture is maintained at the desired temper-

ature. The lower excesses may range from between 1 to 10 or even as high as 30 mols per mol of monoolefin reactant. Equal molar quantities of isoparaffin to monoolefin are, however, contemplated, although it is preferred to employ from 8 to 14 mols of isoparaffin per mol of monoolefin in the reaction mixture.

EXAMPLE 3

10 The following data illustrate the results obtained in a commercial scale unit where the spent acid catalyst discarded from the butene-isobutane reaction zone was used to replace spent catalyst discarded from the pentene-isoparaffin reaction zone. The overall results obtained when the pentene reactor catalyst was maintained at about 90% titratable acidity are compared with similar results obtained when the pentene reactor catalyst was lowered and maintained at about 84% titratable acidity.

15 In this unit, a refinery C₄ stream containing about 12 volume per cent of butenes and about 17 volume per cent of isobutane was divided and charged to each of two jet-type reactors, A and B; a refinery C₅ stream containing about 38 volume per cent of pentenes was also charged to a third jet-type reactor, C. All of the reactors were refrigerated to control the reaction temperature by evaporating part of the light components and withdrawing them from the tops of the reactor towers. After compressing, cooling and liquefying these evaporated light components, they were mixed into a stream of field butanes which had been separated from natural gasoline by fractional distillation. The resultant mixture, which now contained 60 to 65 volume per cent of isoparaffins but substantially no olefins, was divided and added to the refinery C₄ and C₅ streams entering the jets near the bottoms of reactors A and C, respectively, in order to maintain a high mol ratio of isoparaffins to olefins in these reaction zones. To achieve a similar object in reactor B, the total product and the unevaporated, unreacted hydrocarbon components recovered from the settler adjoining reaction zone A were combined with the olefin bearing feed to this reactor. An emulsion, consisting of sulfuric acid catalyst, unreacted paraffin hydrocarbons and alkylation product, was withdrawn near the top of each reactor tower. One part of this emulsion from each reactor was recycled back to its respective reaction zone while the other part was piped into an adjoining settler where it was separated into hydrocarbon and acid phases. Most of the acid separated in each of the three settlers was recycled back to its respective reactor; however, in order to maintain the acid strength above 90% titratable acidity in reactors A and B, a small proportion of the acid in settlers A and B was continuously withdrawn and replaced with fresh 96.5% sulfuric acid. The acid discarded from these two settlers, however, was still useful in catalyzing alkylation of isoparaffins with pentenes.

60 During one operation indicated in the following table, the entire quantity of butene-spent catalyst discarded from settlers A and B was used to replace pentene-spent catalyst continuously discarded from settler C. (Run No. II.) In the other operation reported in the table, only about half of the spent catalyst discarded from settlers A and B was utilized to continuously replace a substantially equal volume of catalyst in settler C. (Run No. I.)

The total alkylation product from the three reactors was withdrawn and combined from settlers B and C before being debutanized and depentanized in distillation towers. Excess isobutane recovered in the debutanization step was readmixed with the field butane stream for recycling to the reactors.

Barrels per day.....	2500	.....	2335			
Volume percent based on olefins charged.....	148	.....	167	30		
Weight percent based on olefins charged.....	171	.....	192			
Yield of aviation alkylate, vol. percent:	68.0	.....	68.0			
Initial boiling point, °F.....	182	.....	182			
50% off at °F.....	220	.....	222			
Final boiling point.....	268	.....	270			
ASTM octane number.....	92.5	.....	92.7	35		

¹ 96.5% sulfuric acid introduced into both reactors A and B to maintain operating level of 93-94%; part of acid discarded from reactors A and B introduced into reactor C to maintain operating level of 82-85%.

² 96.5% sulfuric acid introduced into both reactors A and B to maintain operating level of 93-94%; all of acid discarded from reactors A and B introduced into reactor C to maintain an operating level of at least about 90%.

The above data indicate that reduction in the titratable acidity of the pentene reactor catalyst did not lower the octane number of the overall product nor reduce the percentage of low boiling fractions in the total alkylate.

Having thus fully described the invention, what is desired to be secured and claimed by Letters Patent is:

1. In a process for the production of normally liquid, branched chain paraffinic hydrocarbons by reacting at least one isoparaffin with at least one monoolefin in the presence of concentrated sulfuric acid under suitable alkylation reaction conditions, the improvements comprising maintaining at least two alkylation zones in series, maintaining substantially different sulfuric acid concentrations between about 80% and about 100% in each zone, introducing into one of said

zones at least one monoolefin having a different degree of alkylation activity from the olefins introduced in the other alkylation zones, correlating the olefin activity and acid concentration so that the olefin having the greatest degree of alkylating activity is in contact with the acid of lowest alkylating concentration, and using the at least partially spent sulfuric acid from one zone in another zone utilizing acid of a lower titratable acidity.

2. The process as in claim 1 wherein butenes are introduced into the first alkylation zone and pentenes are introduced into the second alkylation zone, wherein the titratable acidity of the sulfuric acid in the first alkylation zone lies between about 90% and 100.6% sulfuric acid and the titratable acidity in the second zone lies between about 82% and about 89.9% sulfuric acid, and wherein the spent acid from the first zone is employed as the alkylating acid in the second zone.

3. A process which comprises reacting isoparaffins with monoolefins containing at least 5 carbon atoms per molecule under alkylation reaction conditions in the presence of a sulfuric acid alkylation catalyst composition which has previously been employed as an alkylation catalyst in the alkylation of isoparaffins with monoolefins having fewer than 5 carbon atoms per molecule and whose catalytic activity has become substantially decreased for promoting the alkylation of the isoparaffins with the said olefins having less than 5 carbon atoms per molecule.

4. The process as in claim 3 wherein the monoolefins reacted are pentenes.

5. The process as in claim 3 wherein the catalyst used has been previously used in alkyinating isoparaffins with C₃-C₄ monoolefins.

6. A process which comprises reacting isobutane with butenes under alkylation reaction conditions in the presence of between about 90% and about 100.6% sulfuric acid and alkylating isopentane with pentenes under alkylation reaction conditions in the presence of substantially anhydrous, at least partially spent, sulfuric acid alkylation catalyst previously employed in promoting the first-mentioned alkylation reaction, the titratable acidity of the pentenes alkylation acid being between about 82% and about 89.9%.

7. The process as in claim 6 wherein the isoparaffin is present in each alkylation reaction in substantial molar excess over the olefins employed.

8. The process as in claim 6 wherein the isoparaffin is isobutane in both alkylation reactions and wherein the isobutane is present in substantial molar excess over the respective olefins employed.

FRED HEDERHORST.
